UNITED STATES PATENT OFFICE.

THOMAS HENRY HYDE, OF NEW KENSINGTON, PENNSYLVANIA.

LATH-MACHINE.

1,178,853.

Specification of Letters Patent. Patented Apr. 11, 1916.

Application filed July 23, 1914 Serial No. 852,577.

To all whom it may concern:

Be it known that I, THOMAS HENRY HYDE, a resident of New Kensington, in the county of Westmoreland and State of Pennsylvania, have invented a new and useful Improvement in Lath-Machines, of which the following is a specification.

This invention relates to a machine for expanding sheet metal for the production 10 of metal laths and similar products.

The object of the invention is to provide a machine of simple form and so designed that all parts are strong and easily accessible and free from intricate and delicate 15 parts which are liable to be broken and get out of adjustment, and, furthermore, a machine so constructed that any individual part may be quickly removed for repair and replaced by another whereby the production 20 of the machine can be kept up practically to its full limit.

For the attainment of the above and other objects the invention comprises a machine constructed, arranged and combined as 25 hereinafter described and claimed.

In the accompanying drawings, Figure 1 is a plan view of the machine, portions being broken out to economize space; Fig. 2 is in part an end view and in part a transverse 30 vertical section through the machine; Fig. 3 is a front elevation showing five units of the machine on an enlarged scale with a portion of the expanded metal produced thereby; Fig. 4 is a detail view of the 35 mechanism for driving the bottom rolls; Fig. 5 is a detail view of the bearing for the worm shaft; Figs. 6 and 7 are detail views of an upper cutter; and Fig. 8 is a plan view of the product produced by the machine.

40 The machine is composed of a number of sections, each of which is a unit and a practically complete machine in itself and capable of performing its own office independently of the other sections or units. Consequently, any breakage requires merely the 45 repairing of the individual section or unit.

The several sections or units are driven from a common source of power and are all mounted upon a suitable base or foundation 50 1. Each section or unit comprises a frame 2 in which is mounted an upper shaft 3 carrying the slitting and expanding cutters 4, 4^a, and a bottom spindle 5 carrying a pair of co-operating feeding and anvil rolls 5, 6^a. The machine illustrated is a double

machine, namely, one operating upon both edges of the sheet simultaneously and consequently the cutters and feed or anvil rolls are arranged in pairs as illustrated. The shaft 3 is mounted in a rear bearing 7 and 60 an intermediate bearing 8 in the frame 2, and its outer end which carries the cutters 4, 4^a, is overhung by the frame member 9 from which depends a bearing member 10 for the extreme outer end of shaft 3. This 65 bearing member 10 is carried by the swinging arm 11 pivoted to the frame at 12, and having an end portion 13 pivoted at 14 and embracing the bearing 10. This construction enables the arm 11 to be swung outwardly to release the bearing 10 from the 70 end of shaft 3.

The bottom spindle 5 has its inner end mounted in an upright bearing member 15 and its outer end supported by a bearing 16 75 which is carried by a swinging arm 17 pivoted at 18 and having an end portion 19 pivoted at 20 and in which the bearing 16 is mounted so that this arm can be readily 80 swung downwardly out of the way to release the spindle 5.

The cutters 4, 4^a are keyed or otherwise suitably secured to a sleeve 22 which is non-rotatably secured in any suitable way to the upper shaft 3 so that said cutters rotate 85 with said shaft. The feed rollers 6 and 6^a are suitably secured to a sleeve 23 which is rotatable on the bottom spindle 5, although, if desired, said sleeve may be non-rotatably secured to the spindle 5. It is preferred, 90 however, to rotate the sleeve on the spindle, leaving the latter non-rotatable, as thereby the bearings at the inner and outer ends of said spindle can be made shorter than would otherwise be the case.

At the entrance end of the machine, that is, the end at which the unslit sheet enters the machine, the feed rolls 6 and 6^a are driven, but toward the rear end of the machine these rolls are not positively driven, it not being necessary because the feed rolls and cutter in advance thereof effect the proper feeding of the sheet. For driving the feed rolls at the entrance end of the machine each sleeve 23 carries a suitable worm wheel 25, each of which is engaged by a worm 26. The worms 26 of the several units in which the feed rolls are positively driven are all secured on a shaft 27 extending longitudinally of the machine and mounted in 105 110

suitable bearings 28 and extending to the entrance end of the machine. At the entrance end of the machine said shaft is provided with a spur gear 29 meshing with a similar gear 30 on a countershaft 31, which is mounted in the bearings 28 and carries a bevel gear 32 meshing with a similar gear 33 on a transverse inclined shaft 34 extending to the rear side of the machine 5 where it is in turn provided with a bevel gear 35 meshing with a similar gear 36 on the drive shaft 37. The shaft 34 at its forward end is mounted in a yoke 38, in the end of whose arms the countershaft 31 is mounted and at its rear end is mounted in a similar yoke 39 whose ends are mounted on the drive shaft 37. The bearings 28 are movable in order to permit the shaft 27 to be dropped when the spindles 5 are lowered, 10 as when changing rollers 6, 6^a. This may be effected in any suitable way, such as by providing a wedge 41 (Fig. 5), which when withdrawn by screw 42, allows the bearing to be lowered.

25 The drive shaft 37 is arranged longitudinally of the machine at the rear thereof, being mounted in suitable bearings 44 secured to the base of foundation 1. This shaft can be driven by any suitable means, either a 30 motor 45 or by belt or otherwise from a suitable source of power. In addition to the bevel gear 36 said drive shaft 37 is provided at intervals with a number of bevel gears 46, each of which meshes with a bevel gear 47. Each of the upper shafts or spindles 3 carries a spur gear 48, and said gears of adjacent shafts or spindles are connected by an intermediate idler 49. The bevel gears 47 are carried by certain ones of the rollers 49. Preferably a connection 46, 47 and 48 from the drive shaft 37 to the upper spindles or shafts 3 is provided for each five 50 units or sections of the machine, but obviously this can be varied as desired or convenient.

The several sections when assembled, and driven as described form in effect a continuous mill into which the flat sheet is entered and from which it emerges in a completely 55 slit and expanded condition. The cutters and feed rollers of the first or entering pair are spaced apart the maximum distance, so as to form the slits and expansions simultaneously at both edges of the sheet. Each succeeding set of cutters, and also of the co-operating feeding and anvil rolls, is set inwardly a distance equal to the width of the strand, so that toward the exit end of the machine the cutters of each pair become 60 closer and closer together, until finally at the end or exit pair there is practically an integral double cutter, and only a single anvil roll. This is one reason why the feed and anvil rolls at the exit end of the 65 machine cannot be positively driven. Another

difficulty in the way of driving the same is that the shaft 34 for driving the same would be in the way of the downwardly extending expanded sheet. The sheet as it passes through the rolls and is slit and expanded 70 drops off on both sides in a somewhat inclined direction, as indicated in dotted lines at 50.

Each of the cutting and expanding rolls 4, 4^a comprises a suitable ring-shaped body 75 provided on its periphery with the curved cutting projections 51, which serve to slit the metal and press the same down in a curved form, as indicated at 52. The spaces or throats 53 between adjacent projections 80 51 provide for the unslit portions or bonds 54 which unite the several strands. The product produced by these cutters has the several strands in arc or curved form, producing a fabric such as shown in Fig. 8. 85 The fabric produced is not a diamond-mesh fabric, but one in which each strand forms an arch, thereby giving a stiffer sheet than ordinary diamond-mesh lathing, and enabling a lighter sheet to be used. Furthermore, 90 the curved formation of the cutting projections prevents to a considerable extent the deformation of the meshes which occurs in the manufacture of a diamond-mesh fabric. In machines of this type the sheet travels at the rate of what may be called the pitch line of the cutters, while the extreme end portions of the cutting projections travel at a greater rate of speed,—being at a 95 greater distance from the center of rotation. 100 With angular shaped projections such as used in the manufacture of diamond-mesh fabrics, the angular end portions due to their greater peripheral travel more or less deform the mesh, while curved cutting projections, as shown, rotate or slide to some extent in the mesh, without deforming the latter to the same extent as with angular cutting projections.

The sheet as it emerges from the machine 110 may be passed immediately into a set of flattening rollers for the purpose of removing any buckling that may have been produced in the operation of the machine. Such flattening rollers are shown in my 115 prior Patent No. 1,057,346, March 25, 1913, and are therefore neither illustrated nor described herein.

The machine described is of simple and strong construction, being free from delicate 120 or intricate parts which are liable to break or get out of adjustment. Furthermore, all of the wearing parts, and particularly the cutters and feeding or anvil rolls are readily accessible for removal, interchange or repair. The cutting instrumentalities are constructed as separate units, each practically independent of the other, so that it is easy to make repairs or replace parts without 125 putting the machine out of operation for 130

- more than a short time. The machine is double, acting upon both edges of the sheet at once, thereby having a maximum output, and at the same time the construction is such that the sheet will feed continuously and uninterruptedly through the machine, and can be readily removed from the machine at any time when it becomes necessary. The cutters when dull can be sharpened by grinding 5 their side faces, and therefore never change their peripheral form, so that the shape of the mesh of the finished sheet remains the same regardless of the number of times the cutters may be ground. The two upper 10 cutters of each pair are spaced apart a distance the width of two strands less than the distance between the preceding set of cutters and form a gage for bringing the cutters to their correct position transversely 15 of the machine. The keyways keying the cutters to their shafts have the same relative position in all of the sections or units so that the cutters are always correctly spaced radially. 20
- 25 The front side of the machine is entirely open so that the finished sheet is free at all times and there is no chance for the work becoming tangled or liable to choke or to hang on any of the machine parts. The machine is capable of expanding metal of 30 any weight or gage, and the expanded sheet has a selvage edge on both sides, and also a rib or unexpanded portion at its center.
- What I claim is:—
- 35 1. In a machine for expanding metal, the combination of a plurality of rotary cutters arranged in pairs in converging series, a plurality of coöperating feed rolls arranged in pairs between said cutters and having 40 edges coöperating with the cutting faces of said cutters, and driving means for said feed rollers connected thereto between the rolls of each pair.
2. In a machine for expanding metal, the 45 combination of a plurality of rotary cutters arranged in pairs in converging series, a plurality of coöperating feed rolls arranged in pairs between said cutters and having edges coöperating with the cutting faces of 50 said cutters, and mechanism for rotating both the cutters and the feed rolls connected
- to said feed rolls between the roller of each pair. 55
3. In a machine for expanding metal, the combination of a frame, an upper shaft carrying a rotary cutter, a bottom spindle journaled at one end in said frame, a movable bearing for the other end of said spindle, a roll on said spindle coöperating with said cutter, and driving means connected to said spindle intermediate said frame and movable bearing. 60 65
4. In a machine for expanding metal, the combination of a frame, an upper driven shaft, a cutter carried thereby, a bottom spindle journaled in said frame, a roll thereon coöperating with said cutter, a swinging movable bearing for the outer end of said spindle, and a driving shaft connected to said spindle between said frame and movable bearing. 70
5. In a machine for expanding metal, the combination of a series of transverse rotary shafts, two cutters carried by each of said shafts, a series of bottom spindles, pairs of rolls mounted thereon and coöperating with said cutters, a longitudinally arranged drive 75 shaft geared to said transverse shafts, a longitudinally arranged countershaft below said spindles and geared to said rolls, between the rolls of said pairs, and a driving connection from said driving shaft to said 80 countershaft. 85
6. In a machine for expanding metal, a series of transverse shafts, pairs of cutters carried thereby, a series of spindles below said shafts, pairs of rolls mounted on said 90 spindles and coöperating with said cutters, a longitudinally arranged countershaft geared to the rolls of said spindles between the rolls of said pairs, a longitudinally arranged drive shaft geared to said transverse 95 shafts, and a bevel-gear-and-shaft connection from said drive shaft to said countershaft.

In testimony whereof, I have hereunto set my hand.

THOMAS HENRY HYDE.
